[57] CLAIM

The ornamental design for a buckle, as shown and described.

DESCRIPTION

FIG. 1 is a top plan view of a buckle showing my new design;

FIG. 2 is a front elevational view thereof with the rear elevational view being identical thereto;

FIG. 3 is a left side elevational view thereof;

FIG. 4 is a right side elevational view thereof;

FIG. 5 is a bottom plan view thereof;

FIG. 6 is a top plan view of a buckle showing a second embodiment of my new design;

FIG. 7 is a front elevational view thereof with the rear elevational view being identical thereto;

FIG. 8 is a left side elevational view thereof;

FIG. 9 is a right side elevational view thereof;

FIG. 10 is a bottom plan view thereof;

FIG. 11 is a top plan view of a buckle showing a third embodiment of my new design;

FIG. 12 is a front elevational view thereof with the rear elevational view being identical thereto;

FIG. 13 is a left side elevational view thereof;

FIG. 14 is a right side elevational view thereof;

FIG. 15 is a bottom plan view thereof;

FIG. 16 is a top plan view of a buckle showing a fourth embodiment of my new design;

FIG. 17 is a front elevational view thereof with the rear elevational view being identical thereto;

FIG. 18 is a left side elevational view thereof;

FIG. 19 is a right side elevational view thereof; and,

FIG. 20 is a bottom plan view thereof.
